COVERALL GARMENT

Althea W. Kunz, Minneapolis, Minn.

Application January 7, 1948, Serial No. 950

4 Claims. (Cl. 2—80)

1

This invention has relation to a garment more especially adapted to be worn by small children while at play, either as an outer garment or as a so-called cover-all garment.

An object of the invention is to provide a garment of the present character which will be of novel and improved construction.

A further object is to provide a garment for children wherein will be incorporated desirable, new and improved features and characteristics of construction.

And a further object is to provide a protective garment intended to be worn by children while at play which will include novel and improved features and characteristics designed to render the garment simple and practical in construction and inexpensive; readily and easily applicable to and removable from a child; conveniently manipulable while on a child to the end that functions of nature can be performed; and liable to remain in its intended position upon the body, legs and feet.

With the above objects in view, as well as others which will appear as the specification proceeds, the invention comprises the construction, arrangement and combination of parts as now to be fully described and as hereinafter to be specifically claimed, it being understood that the disclosure herein is merely illustrative and intended in no way in a limiting sense, changes in details of construction and arrangement of parts being permissible as long as within the spirit of the invention and the scope of the claims which follow.

In the accompanying drawings forming a part of this specification.

Fig. 1 is a front view and Fig. 2 is a rear view of a garment made according to the invention as it would appear when upon a child with leg and foot straps of the garment in unapplied position;

Fig. 3 is an enlarged rear view of the garment corresponding generally with the disclosure of Fig. 2, but showing a rear central flap and rear side portions of said garment as when in unconnected and open condition; and

Figs. 4, 5 and 6 are fragmentary perspective views each disclosing the rear side of a lower portion of a leg member and a foot member with sole of the garment, Fig. 4 disclosing said leg and foot members as when the rear central flap and a lower part of the rear side portion at the corresponding side of said garment are in unconnected, open condition, Fig. 5 disclosing the leg and foot members as when said rear

2

central flap and said lower part of said rear side portion are in closed, connected condition and the corresponding leg and foot strap is being manipulated to applied position, and Fig. 6 disclosing said leg and foot members as when the rear central flap and said lower part of said rear side portion are in closed, connected condition and said corresponding leg and foot strap is in applied, fastened position.

10 The garment herein presented includes a pair of longitudinally extending portions, the one right and the other left, providing a body member 10, leg members, denoted 11 and 12, respectively, and foot members, indicated 13 and 14, respectively, and said garment also includes straps 15, one of which is between each set of contiguous leg and foot members 11, 13 and 12, 14 at the corresponding side of the garment, and a desirably seamless, flat sole member 16 for each of the foot members 13 and 14.

15 As shown, the body member 10 consists of two longitudinally extending, body covering side pieces, represented 17 and 18, respectively, joined at the center of the front of the garment by a longitudinal seam 19, although said body member could be constituted as a single piece of suitable material, and including rear side portions, indicated 23 and 24, respectively, adapted to be detachably connected along a longitudinal line 25 at the center of the rear of said garment by fasteners 20. The body member 10 is openable along the full length of the rear side portions 23 and 24, and the fasteners 20 may be of any ordinary or preferred character. Sleeves on the body member 10 are designated 21, and a neck band is denoted 22.

20 Each of the leg members 11 and 12 is constituted as a continuation of the body member 10, and the leg members are independent of each other. Each of the foot members 13 and 14 is a continuation of the leg member at the corresponding side of the garment. The leg and foot members 11, 13 and 12, 14 are adapted to cover a wearer's legs and feet and each is continuous at 25 the front of the garment. The leg and foot members 11 and 13 are defined at the exterior side of the rear of the garment by a rear side portion 25 which is a continuation of and extends downwardly and outwardly from the rear side portion 23, and the leg and foot members 12 and 14 are defined at the exterior side of the rear of said garment by a rear side portion 26 which is a continuation of and extends downwardly and outwardly from the rear side portion 24. The free, 30 inner edges of the rear side portions 25 and 26

3

are substantially straight and extend from the lower ends of the free, inner edges of the rear side portions 23 and 24, respectively, to about the location of the rear end of the sole member 16 at the corresponding side of the garment.

The leg and foot members 11, 13 and 12, 14 are defined at their rearward, interior sides by a rear central flap 27 of general V-shape which also comprises a rear closure element. The interior edges of said rear central flap when in closed condition are contiguous with a lower central part of the front of the body member 10, as well as with said leg and foot members, the V-shape rear central flap or rear closure element extends both upwardly and outwardly to be in overlapping relation with both of the rear side portions 25 and 26 of the leg and foot members and also with lower parts of the rear side portions 23 and 24 when these are in connected relation and the rear central flap or rear closure element also is in closed condition, and the exterior edge portions of said rear central flap or rear closure element and the interior edge portions of said rear side portions 25 and 26 support complementary fasteners 28 for detachably connecting the rear central flap or rear closure element to said rear side portions 25 and 26.

It will be apparent that the garment can be opened up at its rear for the full length of the body member 10 and leg members and also substantially for the full length of the foot members, as in Fig. 3 of the drawings, when said garment is to be applied to or removed from a wearer. Thus the garment is adapted to be readily and easily placed upon and removed from a child. Also it will be apparent that the garment is conveniently manipulable while on a child when functions of nature are required to be performed.

The construction and arrangement will be such that the foot members 13 and 14 will be more or less snugly fitted to a child's shoes or feet when the garment is properly placed on the child, with the sole members 16 up against the soles of the child's shoes, or against the bottoms of the child's feet in any instance when the garment is placed on a child while not wearing shoes, and the straps 15 are adapted to be applied in snug, encircling relation to the leg and foot members, at the meeting locations of the leg members 11, 12 with the foot members 13, 14, respectively, in such manner as to insure that the foot members 13 and 14 and the sole members 16 will remain in their intended, fitted positions to a child's shoes or feet.

Each strap 15 includes an intermediate part thereof secured, as at 29, to a rearward part of the garment at the location where the corresponding leg and foot members, 11, 13 or 12, 14, as the case may be, meet, and free end portions thereof adapted to be wound about the leg and foot members, as disclosed in Figs. 5 and 6. Complementary fasteners 30 on outer end parts of the free end portions of the straps 15 can be of any ordinary or preferred construction. Desirably, an intermediate part of one of the free end portions of each strap 15 will include an opening 31 through which the other free end portion can be threaded, as in Fig. 5, and the fasteners, such as 30, when joined will be situated at the rear of the garment, as in Fig. 6, thus to be more apt to remain connected than would be the case were the fasteners situated at the front of the garment. That is, fasteners at the rear of the feet of a creeping child are less liable to become accident-

4

tally undone than are fasteners at the front of the feet.

When the leg and foot straps 15 are applied and connected, as in Fig. 6 of the drawings, the foot members 13 and 14 will be fastened on a child's shoes after the fashion of ordinary rubbers, or on a child's feet after the fashion of ordinary shoes, and not liable to become displaced even by doubling up action of the child as when creeping.

In the disclosure as made, 32 indicates reinforcing pieces on the front portions of the leg members 11 and 12. It will be apparent that the provision of reinforcing pieces is optional.

The garment is for protectively covering a wearer, excepting the upper portion of the neck and the head. When the garment is to be applied or removed, it can be opened up for the full length of the body member 10, for the full length of the leg members 11 and 12 and for substantially the full length of the foot members 13 and 14. Should it be necessary to open up the rear closure element 27, as, for instance, to remove and replace a diaper, said rear closure element can be opened up to substantially completely uncover the space between the inner edges of the rear side portions 25 and 26. And when the garment is in closed condition on a child and the straps 15 are situated in their applied, fastened position, as in Fig. 6 of the drawings, said garment is liable to remain in its intended position on the child's body, legs and feet, as will be apparent.

What is claimed is:

- 35 1. A garment comprising a pair of longitudinally extending portions, the one right and the other left, providing a body member, leg members and foot members, and a sole member for each foot member, said body member consisting of two longitudinally extending, body covering side pieces connected at the front of said garment and including first rear side portions, first means for detachably connecting said first rear side portions along a line extending substantially longitudinally of the body member at the rear of the garment, each of said leg members being connected with a longitudinally extending portion of said body member and each of said foot members being connected with a leg member at the corresponding side of the garment, each set of leg and foot members being connected at the front of the garment, the sets of leg and foot members being defined at the exterior sides of the rear of the garment by second rear side portions which are continuations of said first rear side portions, respectively, and said sets of leg and foot members being defined at their rearward, interior sides by a rear central flap comprising a rear closure element having interior edges thereof connected
- 40 2. The garment of claim 1, with the sets of leg and foot members being connected at the front of said body member, the rear central flap extending upwardly and exteriorly to be in proximate relation to said second rear side portions of the sets of leg and foot members and to lower parts of said
- 45 3. The garment of claim 1, with the sets of leg and foot members being connected at the front of the garment, the sets of leg and foot members being defined at the exterior sides of the rear of the garment by second rear side portions which are continuations of said first rear side portions, respectively, and said sets of leg and foot members being defined at their rearward, interior sides by a rear central flap comprising a rear closure element having interior edges thereof connected
- 50 4. The garment of claim 1, with the sets of leg and foot members being connected at the front of said body member, the rear central flap extending upwardly and exteriorly to be in proximate relation to said second rear side portions of the sets of leg and foot members and to lower parts of said
- 55 5. The garment of claim 1, with the sets of leg and foot members being connected at the front of the garment, the sets of leg and foot members being defined at the exterior sides of the rear of the garment by second rear side portions which are continuations of said first rear side portions, respectively, and said sets of leg and foot members being defined at their rearward, interior sides by a rear central flap comprising a rear closure element having interior edges thereof connected
- 60 6. The garment of claim 1, with the sets of leg and foot members being connected at the front of said body member, the rear central flap extending upwardly and exteriorly to be in proximate relation to said second rear side portions of the sets of leg and foot members and to lower parts of said
- 65 7. The garment of claim 1, with the sets of leg and foot members being connected at the front of the garment, the sets of leg and foot members being defined at the exterior sides of the rear of the garment by second rear side portions which are continuations of said first rear side portions, respectively, and said sets of leg and foot members being defined at their rearward, interior sides by a rear central flap comprising a rear closure element having interior edges thereof connected
- 70 8. The garment of claim 1, with the sets of leg and foot members being connected at the front of said body member, the rear central flap extending upwardly and exteriorly to be in proximate relation to said second rear side portions of the sets of leg and foot members and to lower parts of said
- 75 9. The garment of claim 1, with the sets of leg and foot members being connected at the front of the garment, the sets of leg and foot members being defined at the exterior sides of the rear of the garment by second rear side portions which are continuations of said first rear side portions, respectively, and said sets of leg and foot members being defined at their rearward, interior sides by a rear central flap comprising a rear closure element having interior edges thereof connected

- 76 10. The garment of claim 1, with the sets of leg and foot members being connected at the front of said body member, the rear central flap extending upwardly and exteriorly to be in proximate relation to said second rear side portions of the sets of leg and foot members and to lower parts of said

sole member for each foot member, said body member consisting of two longitudinally extending, body covering side pieces including first rear side portions, first means for detachably connecting said first rear side portions along a line extending substantially longitudinally of the body member at the rear of the garment, each of said leg members being connected with a longitudinally extending portion of said body member and each of said foot members being connected with a leg member at the corresponding side of the garment, each set of leg and foot members being connected at the front of said garment, the sets of leg and foot members being defined at the exterior sides of the rear of the garment by second rear side portions which are continuations of said first rear portions, respectively, and extend to locations adjacent said sole members, respectively, and said sets of leg and foot members being defined at their rearward, interior sides by a rear central flap comprising a rear closure element having interior edges thereof connected with the sets of leg and foot members, respectively, and with a lower part of the front of said body member, the rear central flap extending upwardly and exteriorly when in closed condition to be in proximate relation to said second rear side portions of the sets of leg and foot members and to lower parts of said first rear side portions when these are in connected relation, and second means for detachably connecting said rear central flap to said second rear side portions substantially along the whole of the lengths of the second rear side portions.

3. The combination as specified in claim 1, a strap upon each of said sets of leg and foot members, each of said straps including an intermediate part thereof secured to a part of the garment

5 at the location where the corresponding leg and foot members meet and free end portions thereof adapted to be wound around said corresponding leg and foot members, and complemental fasteners on outer end parts of the free end portions of each of said straps.

10 4. The combination as specified in claim 1, a strap upon each of said sets of leg and foot members, each of said straps including an intermediate part thereof secured to a rearward part of the garment at the location where the corresponding leg and foot members meet and free end portions thereof adapted to be wound around said corresponding leg and foot members, one of the free end portions of each of said straps including an opening through which the other free end portion can be threaded, and complemental fasteners on outer end parts of the free end portions of each of said straps.
